UNITED STATES PATENT OFFICE.

WALTER K. THOMAS, OF NEW YORK, N. Y.

STRIP FEEDING AND CUTTING MACHINE.

1,150,906.

Specification of Letters Patent. Patented Aug. 24, 1915.

Application filed October 17, 1910, Serial No. 587,403. Renewed July 12, 1915. Serial No. 39,517.

To all whom it may concern:

Be it known that I, WALTER K. THOMAS, a citizen of the United States, residing at 1876 Broadway, New York city, county of New York, State of New York, (post-office address 1876 Broadway,) have invented certain new and useful Improvements in Strip Feeding and Cutting Machines, of which the following is a full, clear, and exact description.

10 My invention relates to improved strip feeding and cutting machines, the same being particularly useful in connection with feeding and cutting off short strips of paper, such as labels, stamps and the like, from a long strip or roll of said stock.

15 In the drawings, Figure 1 is a side elevation of my invention before the strip is applied. Fig. 2 is a plan view of the mechanism assembled with the strip in place but partly broken away. Fig. 3 is a side elevation, with one side plate removed. Fig. 4 is a detail. Fig. 5 is a longitudinal section of the removable liquid font and moistening roll support. Fig. 6 is a view of that 20 end of one of the feed rolls opposite to the gear, said view illustrating a pawl and ratchet connection between said feed roll and its combined driving shaft and pivotal 25 mounting.

30 1 represents a reel, upon which a long strip of the material to be fed and cut is mounted.

35 2—2^a represent the side plates of a frame, the same supporting the reel 1 in any desired manner.

40 3—4—5—6 are two sets of companion rollers which are by preference employed, substantially as shown in Fig. 3, the rolls 3—4 constituting one set, the rolls 5—6 the other set. The rolls 3—6 are essentially the feed rolls while the roll 5 is one convenient form of a support or guide. The roll 4 is employed as the moistening roll, that part 45 of the surface thereof in the path of travel of the strip being arranged to take up moisture and convey it to the strip, as later described.

50 7 is a removable font for the moistening fluid, the same likewise being provided with suitable bearings for carrying the roll 4, so that said font and roll may be bodily removed at any time for any purpose.

55 The shafts of the rolls 3—6 are provided with wheels, preferably gear wheels, 3^a—6^a, which are arranged to coöperate with a side

rack 8, which is arranged to be moved to and fro, in this instance a suitable handle being provided on the rack whereby the same may be manually moved. The connection between the gear wheels 3^a—6^a and the rolls 3—6 is preferably a pawl and ratchet connection, as indicated at 9—10 Fig. 6 whereby the gears 3^a—6^a will be positively coupled with said rolls when the latter are to be moved in a direction to feed the strip.

10 11 is a knife arranged to move up and down in guide-way grooves in the side plates 2—2^a. 12 is a second knife element preferably mounted in oblique grooves in the upper part of the frame for adjustment to and fro relatively to the knife 11. The parts 11—12 coöperate in the act of cutting the strip. When the knife element 12 is made adjustable, as preferred, any suitable 75 adjusting means may be employed, for example, adjusting screws 13 and the lock screw 13^a. The passage way for the strip is preferably bounded by suitable guiding means to cause the strip passing from the feed rolls 6 to the feed roll 3 to follow a proper course. This guiding means may comprise the guide pieces 14—15—16—17, the design of which may be varied at will.

15 18 is a guide plate preferably provided to 80 the rear of the feed roll, 6, between it and the reel 1.

19 is a lever pivoted at 20 and carrying an operating arm 21. In the particular form shown herein, the operating arm 21 has an 90 upwardly curved cam portion, as shown in Fig. 1, the extreme end of which is arranged preferably underneath the rack 8.

20 22 is a pawl carried by the rack 8 on a pivot 23. This pawl is preferably pendant 95 from said rack and may swing up in one direction freely, but is checked in its pendant position on its return. By the means of the pawl 22, the arm 21 and the knife 11 are actuated.

25 In the preferred construction, the feed rolls 3—6, the knife element 12 and the guide pieces 14—17 are preferably carried by a hinged portion 24 of the frame, said portion 24 being pivoted, for example, at 100 25, whereby said hinged portion may be elevated, or tilted up, to facilitate threading the strip through the guide passage and under the feed roll 6 (see Fig. 1). When this is done, the hinged part 24 is restored to its normal position and locked in any 105 suitable way, as by a slide bolt 26.

27 is a spring preferably employed to return the rack to its normal idle position. Starting with the rack in the position indicated in Fig. 1, and with the balance of 5 the parts in the position indicated in Fig. 3, and with one end of the strip 29 threaded underneath the roll 6 and up to the knife 11; if the operator now pulls the rack to the left, it will cause the feed rolls 3—6 to 10 rotate in a direction to feed the strip forwardly. As shown herein, the gear wheels 3^a—6^a are of a smaller diameter than the rolls 3—6 respectively, which is a preferred construction, in order that by a relatively 15 short movement of the rack a greater length of strip may be fed per stroke. As the rack is drawn to the left, as viewed in Fig. 1, the strip will be rapidly fed toward and between the rolls 3—4. On the start of said 20 stroke, the pawl 22 trips freely over the end of the arm 21 without disturbing the position of the latter. When the desired length of strip has been withdrawn, the rack 8 is returned to its original position. Near the 25 end of the return stroke the pendant pawl 22, now held rigidly, engages the cam portion of the arm 21 and quickly tilts the same, imparting to the knife 11 a correspondingly quick upward movement, breaking 30 or shearing the strip at a point directly above said knife. The moment the pawl passes the arm 21, the knife resumes its normal position under the influence preferably of a spring of any suitable design, 35 one example of such spring being shown at 28, Fig. 3.

From the foregoing it is apparent that predetermined lengths of strip may be fed out and severed, the length of said strip 40 being determined by the degree to which the rack is moved. If at any time it should be desired to secure a single length of strip of greater length than would be furnished by one full stroke of the rack, all that is 45 required of the operator is to pull the rack to its outer position so as to project the end of the strip beyond the feed roll 3. By continuing to hold the rack in this position, the operator may grasp the projected strip 50 end and pull it out any desired length, the rolls 3—6 freely permitting this withdrawal of the strip by reason of their ratchet mounting the teeth of the ratchets *c* being so set as to permit the pawl 10 to ride there- 55 on with the continued rotary movement of the rolls 3 and 8 incidental to such withdrawal of the paper. Again, the operator may project as long a strip as desired by simply reciprocating the rack to and fro, 60 taking care on each reciprocation not to permit said rack to return to such a degree as to cause the pawl 22 to engage and operate the arm 21.

It is obvious that in a variety of ways 65 the machine herein described may be modi-

fied without departing from the spirit or scope of this invention, and for that reason it should be understood that the foregoing description attempts to describe in terms only one preferred and successful form.

Many advantages are attained in the use of this machine; for example, where a gummed strip is used, the unused end which remains in the machine stands at a point well removed from the moistening roll, so that there is no danger of prematurely moistening the same. Again, it will be observed that the cutting off operation occurs at a point where as yet the strip is unmoistened, thereby avoiding the gumming up of the 75 knife. Again, it holds the severed strip conveniently so that where the same is to be applied to a package its exposed and moistened end may be applied to the package before withdrawing the balance of the 80 strip, thus enabling such gummed strip to be readily attached to packages without soiling the fingers. In the preferred construction, the distance from the rear of the knife to the top of the moistening roll is 85 such that on starting the machine sufficient time will be permitted for the moistening roll to revolve to such a degree as to present a freshly moistened surface to the strip by the time the oncoming end of the strip 90 reaches said roll. The feed rolls 3—6 are preferably metallic and provided with slight knurlings or nibs arranged to assist in feeding the paper, while the opposite rolls 4—5 preferably have relatively soft surfaces. It 95 should be stated that the preferred form of the knife 11 is such that it provides, in connection with the knife element 12, a shearing action. Again, it is preferred that the two opposite edges of the knife 11 be 100 provided with upward extensions 11^a—11^a, which stand flush with the inner surfaces 105 of the side plates of the frame, and likewise project at all times slightly above the lower end of the knife element 12, whereby it is 110 never possible to project the knife element 12 across the path of movement of the blade 11. Any suitable means may be provided for adjusting the rolls so as to vary the 115 space between them. Such modifications are too obvious to require illustration or detailed description.

What I claim is:

1. In a strip feeding and cutting machine a plurality of parallel rolls, a plurality of 120 gears, pawl and ratchet connection between said gears respectively and said rollers respectively, whereby said rolls may be simultaneously and positively driven in one direction only, a cutter intermediate said rolls, a roll bearing upon each of said first named rolls, a rack in mesh with both of said gears, means adapted to actuate said cutter, means 125 movable with said rack and adapted to operatively engage said last named means to 130

actuate said cutter, and a fountain from which moisture is applied to the strip by the roll coöperating with the positively driven roll in advance of said cutter.

- 5 2. In a strip feeding and cutting machine, a plurality of parallel rolls, a plurality of gears, a pawl and ratchet connection between said gears respectively and said rolls respectively, whereby said rolls may be simultaneously and positively driven in one direction only, a fixed and movable cutting blade intermediate said rolls, a roll bearing upon each of said first named rolls, a reciprocatory rack in mesh with both of said
- 10 gears, an operating lever connected with said movable cutting blade, a pivotal member carried by said rack and adapted to operatively engage said lever upon the reciprocation of said rack, and a fountain from which moisture is applied to the strip by the roll coöperating with the positively driven roll in advance of said cutting blades.

- 15 3. In a strip feeding and cutting machine, a frame including a main frame portion having a guide passage thereon and a movable portion hinged adjacent one end of said passage, a plurality of parallel rolls mounted in said hinged portion, a fixed cutter blade carried by said hinged portion, means carried by said rolls whereby they may be simultaneously actuated, a roll adapted to bear upon each of said first named rolls mounted in said main frame portion, a movable cutter blade carried by said main frame portion, main actuating means adapted to operatively engage the means carried by said first named rolls, means whereby said movable cutter blade may be actuated, means carried by said main
- 20 40 actuating means and adapted to operatively engage means for actuating said movable cutter blade, and a fountain from which moisture is applied to the strip by the roll coöperating with the roll mounted on said movable portion in advance of said cutting blades.

- 45 4. In a strip feeding and cutting mechanism, a frame, a feed-roll, a moistening roll adjacent thereto and removable laterally from said frame, a guide at the rear of said feed and moistening rolls, a cutter likewise at the rear of said rolls and arranged to move across the path of movement of a strip being drawn through said rolls, operating means in common to said feed-roll and said cutter, and an adjustable coöperating cutter element arranged obliquely to the path of travel of said first mentioned cutter element.

- 50 5. In a strip feeding and cutting mechanism, a frame, a feed-roll, a moistening roll adjacent thereto and removable laterally from said frame, a guide at the rear of said feed and moistening rolls, a cutter likewise at the rear of said rolls and arranged to move across the path of movement of a strip

being drawn through said rolls, operating means in common to said feed roll and said cutter, an adjustable coöperating cutter element arranged obliquely to the path of travel of said first mentioned element, part 70 of the first mentioned cutter element overlapping at all times said second cutter element to prevent the second mentioned cutter element from being adjusted to such a position as to interfere with the movement of 75 said first mentioned cutter element.

6. In a strip feeding and cutting machine, a frame, two feed-rolls having a guide passage between the same, a moistening element adjacent to the outermost feed-roll, a reciprocating operating device for said feed-rolls and said cutter, said operating device moving said feed-rolls when said operating device is moved in one direction, and operating said cutting device when moved in an 80 opposite direction only, and connections between said operating device and cutter, including a curved lever carried by said frame and a lever engaging pawl carried by said operating device.

7. In a strip feeding and cutting machine, a reel, a feed-roll, a ratchet mounting therefor including a gear, a rack in operative engagement with said gear and arranged to turn said feed-roll when said rack is moved in one direction, a cutter between said reel and said feed-roll, operative means of connection between said cutter and said rack, including a lever adapted to reciprocate the former and a pawl on the latter, whereby said cutter is actuated only when said rack is moved in an opposite direction to that first mentioned, a moistening roll arranged 95 adjacent to said feed-roll, and means at the rear of the cutter to feed the strip forwardly.

8. In a strip feeding and cutting machine, a frame, a reel, a feed-roll, a pawl and ratchet mounting therefor including a gear, a rack in operative engagement with said gear and arranged to turn said feed-roll only when said rack is moved in one direction, a cutter between said reel and said feed-roll, operative means of connection between said cutter and said rack, including a lever adapted to reciprocate the former and a pawl on the latter, whereby said cutter is actuated only when said rack is moved in an opposite direction to that first mentioned, a moistening roll arranged adjacent to said feed-roll, a removable font carrying said moistening roll, said font being removable laterally from said frame, and means at the rear of the cutter to feed the strip forwardly.

9. In a strip feeding and cutting machine, a reel, a feed-roll, a ratchet mounting therefor including a gear, a rack in operative engagement with said gear and arranged to turn said feed-roll only when said

rack is moved in one direction, a cutter between said reel and said feed-roll, operative means of connection between said cutter and said rack, including a lever adapted to reciprocate the former and a pawl on the latter, whereby said cutter is actuated only when said rack is moved in an opposite direction to that first mentioned, a moistening roll arranged adjacent to said feed-roll, and 10 another feed-roll arranged between said cutter and said reel.

10. In a strip feeding and cutting machine, a reel, a feed-roll, a ratchet mounting therefor including a gear, a rack in operative engagement with said gear and arranged to turn said feed-roll when said rack is moved in one direction only, a cutter between said reel and said feed-roll, operative means of connection between said cutter 15 and said rack whereby said cutter is actuated when said rack is moved in an opposite direction to that first mentioned, a moistening roll arranged adjacent to said feed-roll, said cutter including two cutter elements, parts of which overlap at all 20 times, one of said elements being adjustable, and means at the rear of the cutter to feed the strip forwardly.

11. In a strip feeding and cutting machine, a reel, a feed-roll, a ratchet mounting therefor including a gear, a rack in operative engagement with said gear and arranged to turn said feed-roll when said rack is moved in one direction only, a cutter between said reel and said feed-roll, operative 30 means of connection between said cutter and said rack whereby said cutter is actuated only when said rack is moved in an opposite direction to that first mentioned, a moistening roll arranged adjacent to said 35

feed-roll, said cutter including two cutter elements, one of said cutter elements being adjustable, a carrier for said feed-roll whereby the same may be lifted, and means at the rear of the cutter to feed the strip 45 forwardly.

12. In a strip feeding and moistening apparatus, a frame, a reel carried thereby, a cutter carried thereby, operating mechanism carried thereby, a moistener carried thereby, said frame having a movable part, a pair of feed rolls carried by said moving part whereby said rolls may be moved from an operative to an inoperative position.

13. In a strip feeding and moistening apparatus, a frame, a reel carried thereby, a cutter carried thereby, operating mechanism carried thereby, a moistener carried thereby, said frame having a movable part, a pair of feed rolls and a strip guide carried 60 by said moving part whereby said rolls may be moved from an operative to an inoperative position.

14. In a strip feeding and moistening apparatus, a frame, a reel carried thereby, a cutter carried thereby, operating mechanism carried thereby, a moistener carried thereby, said frame having a movable part, a pair of feed rolls carried by said moving part whereby said rolls may be moved from 65 an operative to an inoperative position, and an adjustable cutter abutment for co-operation with the cutter, said cutter abutment being carried by the movable part of said frame.

WALTER K. THOMAS.
